(57) **CLAIM**

We claim the ornamental design for water filter suspension apparatus, as shown.

DESCRIPTION

FIG. 1 is a perspective view of the water filter suspension apparatus according to an embodiment of the present invention.

FIG. 2 is the top view of the water filter suspension apparatus shown in FIG. 1;

FIG. 3 is the bottom view of the water filter suspension apparatus shown in FIG. 1;

FIG. 4 is the front view of the water filter suspension apparatus shown in FIG. 1;

FIG. 5 is the back view of the water filter suspension apparatus shown in FIG. 1;

FIG. 6 is the right side view of the water filter suspension apparatus shown in FIG. 1;

FIG. 7 is the left side view of the water filter suspension apparatus shown in FIG. 1;

FIG. 8 is an environmental perspective view of the water filter suspension apparatus shown in FIG. 8;

FIG. 9 is an environmental front view of the water filter suspension apparatus shown in FIG. 8; and,

FIG. 10 is an environmental top view of the water filter suspension apparatus shown in FIG. 8.

The broken lines in the Figures show the environment of the claimed water filter suspension apparatus. The broken lines in all of the Figures form no part of the claimed design.
